WRINGER ROLL TENSIONING

Nicholas L. Etten, Waterloo, Iowa, assignor to
Chamberlain Corporation, Waterloo, Iowa

Application June 5, 1935, Serial No. 25,036

12 Claims. (Cl. 68—262)

This invention is directed to a releasable means for tensioning wringer rolls and has for one of its objects to provide a mechanism capable of bringing about resiliently applied pressure between wringer rolls, which consists of a novel mechanism disposed within one of the rolls.

Another object is to provide a tensioning element disposed within one of the rolls the same having connected mechanism disposed outside the rolls for stressing the element to cause the rolls to press together.

A further object is to provide mechanism as aforesaid and co-operative mechanism to releasably hold the tensioning element in stressed condition.

An additional object lies in the provision of a tensioning element disposed within a wringer roll, capable, when under stress, of bringing about resiliently applied pressure between the rolls of a wringer, manually operable means for operating the element to place it in stressed condition, and co-operative mechanism for holding the element in the latter condition.

It is further an object to provide a wringer mechanism including dual rolls, at least one of said rolls having means disposed within it for causing the rolls to be pressed together.

Another object is to provide a wringer mechanism including dual rolls, at least one of said rolls having a torsionally stressable member disposed within it which is operable when under stress, to press the rolls together, manual means for bringing about a stressed condition in the element and releasable means for holding the element in stressed condition.

Other objects will appear in the following description and accompanying drawings in which:

Fig. 1 is a side elevational view showing my device as the same would appear ready for operation;

Fig. 2 is a fractionated front elevational view wherein the entire front sections of the upper frames 11 and 12 are broken away and the handle control parts 37, 38 and 41 removed to disclose the arrangement of the other parts.

Fig. 3 is a fractional endwise elevational view taken on line 3—3 in Fig. 2;

Fig. 4 is a fractional sectional endwise elevational view taken on line 4—4 in Fig. 2;

Fig. 5 is a sectional elevational view showing mechanism disposed within the lower roll of my wringer;

Fig. 6 is an end elevational view taken from line 6—6 in Fig. 5;

Fig. 7 is a view similar to Fig. 6 showing certain parts in operated position;

Fig. 8 is a plan view showing the device as it would appear as though viewed from line 8—8 in Fig. 1.

Fig. 9 is a view similar to that shown in Fig. 8 with portions of the frame removed to expose interior mechanism, the same being taken from line 9—9 in Fig. 1; and

Fig. 10 is an enlarged end elevational view showing details of construction to be referred to.

Figs. 1 and 2 of the drawings disclose my device as generally comprising a frame 10 which includes upright end portions 11 and 12, and upper and lower rolls 13 and 14. The frame 10 is provided with conventional drain boards 15 extending downwardly and outwardly upon each side of the wringer.

The lower roll 14 is supported in the frame by means of its shaft ends 14'—14' journaled in bearing blocks 16 which latter rest upon extensions 17 of the frame structure. At the right hand end, the shaft 14' of roll 14 is extended as shown, which extension provides means for driving connection with a power source not shown.

The upper roll 13 is supported in a special manner now to be described.

Fig. 5 illustrates that the upper roll comprises a tube member 18 which is surrounded by a layer of rubber 19, the external appearance being substantially similar to that of lower roll 14.

Within each end of tube 18 there is disclosed a plug member, 20 and 21 respectively.

The tube is rotatably fitted upon the plugs and the roll is thus made freely rotatable upon the plugs.

The plugs have skirt portions 22 and 23 which provide elongated bearing surfaces for the plugs.

Within the inner body portions of the plugs are apertures 24 which are herein shown as having a rectangular cross section, adapted to receive opposite ends of a spring member 25. The spring has a rectangular cross section of dimensions suitable to fit the apertures 24 whereby the spring ends are held in keyed relation with the plugs. It is to be noted that the rectangular spring is herein shown as an illustration only. Any form of spring having suitable characteristics may be employed.

Plug 21 carries an arm 26 fixed thereto as by set screw 26' and plug 20 carries a similar member 27 which is not fixed, but is made to allow free rocking movement of the plug within it.

An arm 28 is affixed to the outer end of plug 20 by set screw 28'.

Fig. 9 discloses that arms 26 and 27 have their outer ends pivotally supported at 29 and 30 upon the wringer frame structure. In view of the disclosure in Figs. 3 and 4 it will be apparent that arms 26 and 27 are adapted to support roll 13 in proper alignment with roll 14 and in a manner to permit movement of the upper roll away from the lower roll which movement would be produced by garments passing between the rolls.

As already noted, plug 20 is made rotatable within arm 27 and arm 28 is affixed thereto.

In Figs. 5 and 6 the arm 28 is shown lying in position opposite arm 27, and spring 25 is shown as in twisted condition. Fig. 6 indicates that arm 28 may be held in the position noted by means of a latch member 31 which will be explained shortly.

This combination of parts forms a lever system consisting of two lever arms joined by a spring wherein the spring 25 through 20 is tensionable to cause rotation but being held by 21 and 26 the lever 28 is forced upward where it reacts against 31 to cause roller 13 to be resiliently held down against roller 14.

Reference has been made to the latch 31. Fig. 3 illustrates that this member forms the lower extremity of a lever 32 which is pivotally supported at 33 upon the wringer frame structure. The upper arm of the lever extends upwardly a short distance above the wringer frame structure and carries one end of a bar 34, Fig. 2, which latter extends across the wringer and has its opposite end attached to an arm 35 which is pivotally supported at 36 in the frame structure. On the opposite side of the wringer are upright arms 37 and 38 pivotally supported at 39 and 40 respectively, and connected by a bar 41 similar to bar 34.

A connecting link 42 connects the arms 35 and 38, it being pivotally attached at 43, above pivot 40, on arm 38 and at 44, below pivot 36, on arm 35. By means of this connection the bars 34 and 41 are made to operate in unison but in opposite directions as indicated in dotted lines in Fig. 3. A spring 45, attached between link 42 and the wringer frame, urges the arms toward upright position, in which position the latch 31 is held in engagement with arm 28.

It will now become apparent that manipulation of either of bars 34 or 41 inwardly, away from an operator positioned on either side of the wringer, will bring about disengagement of the latch from arm 28 as shown in dotted lines in Fig. 7.

Thus disengaged, arm 28 is free to rotate clockwise responsively to the tension of spring 25 to relax the spring and render it incapable of holding the upper roll in pressure relationship with the lower roll. With the parts in this position the roll may rock freely upon arms 26 and 27.

To reset the tensioning mechanism I provide a mechanism best shown in Figs. 2, 9 and 10. This device consists of a crank member 46 disposed outside the wringer frame structure and affixed to a shaft 47 which is journaled in the structure and carries an affixed arm 48 disposed adjacent the arm 28.

A roller 49 is mounted upon the end of arm 48 and is disposed in the path of movement of arm 28.

Crank 46 normally rests in the full line position shown in Figs. 9 and 10, with roller 49 in corresponding position. When arm 28 is released it will obviously rotate into position adjacent roller 49 after which, to reset the arm, crank 46

is rotated counterclockwise, Fig. 10, whereupon roller 49 will engage the arm and force it backwardly to be engaged by latch 31. Crank 46 is then returned to normal position.

It will be noted that the center of shaft 47 is disposed offset from the axial center of roller 13 whereby the roller 49, at the beginning of its resetting stroke, is placed somewhat near the center of rotation of arm 28 whereas at the end of the stroke it is engaged at a point considerably further from this center. This arrangement increases the ease with which resistance of spring 25 may be overcome, this by reason of the force exerted on crank 46 being applied to greater advantage as the resistance of spring 25 increases.

To prevent longitudinal movement of roll 13 I provide that the outer end of plug 21 may engage an abutment member 50 and the outer end of plug 20 abuts the inner face of arm 48.

The foregoing has described an embodiment of my invention. Modifications are obviously possible without alteration of the principle involved. I do not wish to be limited in structure or principle except within the scope of the appended claims.

What I claim is:

1. A device of the class described, a frame having therein upper and lower wringer rolls in combination with means for holding the rolls in pressure relationship comprising, an arm supported in one end of one of the rolls for pivotal movement in the plane of rotation of the roll, a second arm similarly supported in the opposite end of the roll, the arms extending from opposite ends of the roll, a resilient member in the roll connecting the arms whereby the arms cooperate to form a lever system embodying a resilient element supported by the roll with the lever made rockable about the relatively fixed center of the roll and means for applying pressure upon the arms in the direction of the other roll whereby the associated roll is forced toward the other roll.

2. A roll wringer mechanism including in combination, a frame having therein a pair of wringer rolls, one of said rolls being movable toward the other and means for holding the rolls in pressure relationship comprising, an arm mounted for pivotal movement in each end of the movable roll, said arms extending from opposite ends of the roll, a torsion spring lying along the axial center of said roll with its opposite ends attached to and connecting the arms within the movable roll to form a lever system embodying a resilient element, the levers being supported in the movable roll normally resting against the opposite roll, and means for pressing the arms toward the opposite roll whereby the arms are rotated in the movable roll in opposite directions and said spring is torsionally flexed to press the movable roll upon the opposite roll.

3. A device as set forth in claim 2, provided with means for quickly releasing one of said arms, freeing it to rotate responsively to tension of the spring whereby the spring is relaxed and pressure between the rolls is removed.

4. A roll wringer mechanism including, a pair of rolls and a supporting frame therefor, one of said rolls being movable toward and from the other, a torsionally active spring mounted in the movable roll in a manner to react upon the fixed roll to press it toward the opposite roll when torsionally stressed, and means connecting the spring with the supporting frame torsionally to stress the spring whereby said spring will press its role toward the other roll.

5. A roll wringer mechanism including, a pair of rolls and supporting frame therefor, said rolls being movable toward and from one another, a torsionally active spring mounted in one of 5 the rolls in a manner to react upon the roll to press it toward the opposite roll when torsionally stressed, mechanism connecting the spring with the supporting frame for stressing the spring in torsional manner to press its supporting roll 10 toward the other roll, and manual means for operating said connecting mechanism to stress the spring.

6. A roll wringer mechanism including, a pair of rolls and a supporting frame therefor, said 15 rolls being relatively movable toward and from one another, a torsionally active spring mounted in one of the rolls in a manner to react upon the roll to press it toward the opposite roll when torsionally stressed, releasable mechanism 20 connecting the spring with the supporting frame for stressing the spring in a torsional manner to press its supporting roll toward the other roll, manual means for operating said connecting mechanism to stress the spring, and manual 25 means for releasing said releasable mechanism.

7. In a clothes wringer, a frame, rolls therein including a driven roll rotatable on a fixed axis, a tubular companion roll, bearings for the latter, 30 rocking arms carrying said bearings at one end each for said companion roll and pivotally secured at their other ends to the wringer frame at co-axial points spaced equally from a plane common to the axes of both rolls, one of said 35 bearings being rigid with its arm and the other being rotatable relatively to its arm, a torsion spring extending through the tubular roll and secured at its ends to said bearings to provide against rotation relatively thereto, a lever arm rigid with the last-named bearing, a trip arm 40 rigid therewith, a manually operable trip-lever disposed on said frame to engage said trip-arm, and a manually operable means mounted upon the wringer frame and engageable with said lever arm to rotate the last named bearing 45 against the action of said spring to cause the trip-arm to engage the trip lever whereby said spring is tensioned to urge the tubular roll against the driven roll.

8. In a clothes wringer, a frame, rolls therein 50 including a driven roll rotatable on a fixed axis, a companion roll, a pair of rocker arms pivotally secured at one end each to the wringer frame at co-axial points spaced equally from a plane common to the axes of both said rolls, a bearing 55 for one end of the last-named roll rigid with one of said arms, a bearing for the other end of said roll rotatably mounted in the other arm, a torsion spring non-rotatably connected with both said bearings and axially disposed thereof, manually operable means for effecting a relative 60 rotation of said bearings for tensioning said spring, and a manually releasable trip mechanism arranged to hold said last-named bearing in the position for maintaining said spring under tension and thereby causing said trip mechanism to cooperate with said spring to maintain the last-named roll yieldably engaged with the driven roll.

9. In a clothes wringer, a frame, rolls therein 70 including a driven roll rotatable on a fixed axis, a companion roll, a pair of rocker arms pivotally secured at one end each to the wringer frame

at co-axial points spaced equally from a plane common to the axes of both said rolls, a bearing for one end of the last-named roll rigid with one of said arms, a bearing for the other end of said roll rotatably mounted in the other arm, a torsion spring non-rotatably connected with both said bearings and axially disposed thereof, a lever arm rigid with the last-mentioned bearing, a crank arm mounted on a pivot 5 rigid with the frame and disposed in a plane offset from the first-named plane, a manually operable trip-mechanism operatively associated with said last-named bearing, and a device on said lever arm disposed for engagement with said crank arm in the direction wherein said lever 10 arm is caused to rotate the last-named bearing to distort the spring and set said trip mechanism, the latter cooperating with said arms to maintain the distortion of the spring and cause the companion roll to be urged toward the driven 15 roll, said offset pivot of said crank-arm acting to increase the leverage exerted upon the lever arm to effect distortion of said spring.

10. In a clothes wringer, a frame, a pair of 20 relatively movable wringer rolls therein, a torsion spring disposed axially of one of said rolls, relatively rotatable bearings for the latter roll non-rotatably secured to opposite ends of said spring, carriers for said respective bearings, a trip mechanism associated with one of the latter, and a 25 manually operable means for rotating the last-named bearing relatively to the other thereof for tensioning said spring and setting said trip-mechanism, whereby to maintain the tension of 30 said spring and causing said trip-mechanism to cooperate with said spring and said carriers to urge the last-named roll toward the other roll.

11. In a clothes wringer, a frame, a pair of 35 relatively movable wringer rolls therein, a torsion spring disposed axially of one of said rolls, relatively rotatable bearings for the latter roll non-rotatably secured to opposite ends of said spring, carriers for said respective bearings, a trip mechanism associated with one of the latter, and a manually operable means for rotating the 40 last-named bearing relatively to the other thereof for tensioning said spring and setting said trip-mechanism, whereby to maintain the tension of 45 said spring and causing said trip-mechanism to cooperate with said spring and said carriers to urge the last-named roll toward the other roll, said manually operable means including means whereby the force exerted to effect tensioning of said spring increases as resistance of said 50 spring increases.

12. In a clothes wringer, a frame, a pair of 55 relatively movable wringer rolls therein, a torsion spring disposed axially of one of said rolls, relatively rotatable bearings for the latter roll non-rotatably secured to opposite ends of said 60 spring, carriers for said respective bearings, a trip mechanism associated with one of the latter, and a manually operable leverage compounding mechanism for rotating the last-named bearing relatively to the other thereof for tensioning 65 said spring and setting said trip-mechanism, whereby to maintain the tension of said spring and causing said trip-mechanism to cooperate with said spring and said carriers to urge the last-named roll toward the other roll.
